UNITED STATES PATENT OFFICE.

ARTHUR WARD, OF GREYSTONE, RHODE ISLAND.

ELECTRIC CONTROL FOR ELEVATORS.

1,160,678.

Specification of Letters Patent. Patented Nov. 16, 1915.

Application filed March 13, 1915. Serial No. 14,166.

To all whom it may concern:

Be it known that I, ARTHUR WARD, a subject of the King of Great Britain, residing at Greystone, in the county of Providence and State of Rhode Island, have invented 5 a new and useful Improvement in Electric Controls for Elevators, of which the following is a specification.

This invention relates to certain new and 10 useful improvements in electric controls for elevators, and pertains more particularly to an elevator in which operation thereof in either ascending or descending is prevented should one of the doors of the elevator shaft 15 be left open.

The present invention is particularly adapted for hydraulic elevators though capable of use with other types of elevators as well.

20 The primary object of the present invention is to provide an improved structure for preventing operation of the elevator in event of one or more of the elevator shaft doors being left open.

25 A further object of the invention is to provide a simple control in which a simple form of switch is mounted on the single or double doors controlling each ingress to the elevator shaft.

30 In the drawings—Figure 1 is a view partly in section of a part of the invention. Fig. 2 is a similar view of another part of the invention, and Figs. 3 and 4 are plan views of the motor reversing switch, showing the latter in its two positions.

35 In the drawings an elevator cage 1 and double doors 2 and 3 for the shaft are shown. At the top of the doorway there is arranged a casing 4 in which the door switches are 40 located. The circuit closer is of the double type in this instance so as to require that both doors be closed before the elevator can be started and includes downwardly movable plates 5 which carry insulation blocks 6 to 45 which latter spring switch blades 7 are centrally fixed, the blades 7 when the doors are closed engaging contacts 8 and when the doors are open engaging contacts 9. The above structure of circuit switch may be 50 best understood from Fig. 2 in which the switch is of the same general type as that above described, the plates 5 being pivoted at 10 and tensioned by coil spring 11, as shown. The lower contacts 9 are in circuit, 55 which will be later hereinafter specifically described, with a magnetic reversing switch

13 while the upper contacts 8 are in circuit, also later hereinafter specifically described, with the magnetic reversing switch 13. An electric motor 15 which has reducing gears 60 associated therewith is in circuit with the reversing switch 13 by means later specifically set forth. When the doors are closed so that the elevator may be operated the balanced valve V of the hydraulic system is 65 in open position and the door switch is held closed by the closed position of the doors. When a door is opened the plate 5 of the door switch will drop, completing the circuit through the motor 15 to rotate the 70 latter to bring the arm 17 into the dotted line position shown in Fig. 1 which through the medium of the cable 18 connected to the weighted arm 19 of valve V permits said weighted arm 19 to drop, closing the valve 75 and thereby preventing operation of the elevator by shutting off communication between the hydraulic cylinder 20 and the piston that operates in cylinder 21. When the door is closed the plate 5 of the door switch will, 80 by reason of being engaged with the door, be moved to closed position, thus closing the circuit through the motor to reversely rotate the latter and to return the arm 17 to its full line position, thus lifting the 85 weighted arm of the balance arm V which will permit the flow of water to operate the hydraulic piston and the elevator.

Referring now to Fig. 2 it will be seen that a fan 22 is pivoted in a casing 23 90 and normally contacts a latch 24 mounted on the end of an arm 25 that is pivoted at 26 and has a depending end 27 arranged adjacent a magnet 28. An armature 29 is arranged on the end 27 of arm 25. The 95 ground which is in the nature of a wheel 30 has two peripheral V-cuts 31 into which a V-shaped locking piece or detent 32' on arm 25 is adapted to engage and when magnet 28 is energized it will attract armature 29 100 and lift arm 25 and therewith the locking piece 32' out of the notch 31 and at the same time raise latch 24 so as to release fan 22, and also lift a bottom spring 32 to contact with a top spring 33 and close the motor 105 circuit, for which purpose a vertical arm 34 depending from arm 25 is connected to the bottom spring arm 32 to release or lift the latter into contact with upper spring arm 33. The fan 22 and wheel 30 are driven 110 from the gearing and may be operated for instance; the fan from the shaft 17' of gear

70, and the wheel 30 from the shaft 17" of gear 71.

The above described means is utilized for the purpose of imparting just sufficient momentum to the motor to effect lifting of arm 19 of valve V or to lower the latter, depending upon the position of the door. One of the circuits operates on the coil of the motor for clockwise rotation, while the other circuit operates through connection with the armature of the motor for counter-clockwise movement.

The reversing switch 13 includes a double set of magnets 35 and 36 and an armature 37 having insulated contacts 38 at its ends, the armature being guided in its movements in the space between the two sets of magnets by any suitable means, for example slots 60 in the switch casing and pins 61 on the armature 37. Terminals 48' are disposed between the two sets of magnets and are connected by wires 62' to the contacts 38 of the armature so as to not interfere with the movements of the latter.

Fig. 2 illustrates the parts and contacts of the circuits as in position when the door or doors were open and the door switch at the instant of the closing of the door or doors to establish the circuit to operate the various parts to lift or open the valve V to the position shown in full lines in Fig. 1.

The operation is as follows: The closing of the door causes blade 7 to occupy the position shown in Fig. 2 in which it engages the terminals 8 whereby a circuit will be established, as follows, namely, from the right hand terminal to wire a through magnets 36; wire b to wire c to contact 43; spring arm 40 of wheel 30 to ground and from the latter to magnet 28 and from the latter through wire d to split 41 and through wire e to the batteries B; from batteries B to wire f; to split 44; wire g to split 45; and from the latter by wire h to the left terminal 8, where it crosses blade 7 to the right terminal.

Magnet 28 is thus energized, attracting armature 29, lifting arm 25 and its parts 24, 25, 32, 32', and 34, releasing fan 22 and wheel 30; thus establishing the motor circuit, and due to the energization of the magnets 36 the armature 37 is attracted thereto as shown in Fig. 3. The motor circuit receives its power from the batteries B and is as follows; raising of arm 34 enables the lower spring arm 32 to rise and engage upper arm 33, thus closing a circuit from terminal 47, wire i to terminal 48 of switch 13; wire 62; contact 38 of armature 37; contact 49; wire j to the motor brush B'; to motor brush B²; through wire k to the contact 49' of switch 13; contact 38'; wire 62' and terminals 48'; through wire l to terminal C of the coil of the motor; through the coil to terminal C' of the coil

through wire m to split 41 and from the latter to wire e to the battery and from the latter through wire f to split 44 and from the latter through wire n to terminal 51 of lower switch arm 32. The motor is thus started, revolving wheel 30 so as to cause spring arm 40 of the wheel 30 to contact with the terminal 52 in which position of the parts arm 17, having been moved to the full line position of Fig. 1, will open valve V, thus enabling operation of the elevator.

When arm 40 of wheel 30 is in engagement with contact 52 and the door of the elevator is opened, plate 5 drops carrying blade 7 therewith and into engagement with contacts 9, whereby a circuit will be established to reverse the direction of rotation of the motor 15 to bring the parts to the dotted line position of Fig. 1 in which the valve V is closed and operation of the system rendered impossible.

The motor reversing circuit is established as follows: From magnet 28; to wire d; to split 41; wire e to batteries; wire f; split 44; wire g; to left terminal 9; blade 7; right terminal 9; wire o; to magnets 35 of the reversing switch 13, which attracts the armature 37 to the position shown in Fig. 4; wire p to terminal 52; arm 40 to ground and from the latter to magnet 28 thereby establishing a reverse motor circuit and the motor is operated but in a reverse direction, as follows—the contacting of the spring 32 with the arm 34 closing a circuit from terminal 47; wire i to terminal 48; wire 62, contact 38, contact 37'; cross-over 63; contact 49'; wire k brush B² to brush B'; wire j to contact 49; cross over 63'; contact 37'; contact 38'; wire 62'; terminal 48'; wire l to terminal C of coil of motor, through coil to terminal C'; wire m to split 41; wire e; battery B, wire f, split 44, wire n, terminal 51; spring 32, arm 34 to terminal 47. As soon as the arm 25 is lifted the rotation of wheel 30 brings the high side thereof beneath locking part 32', thus preventing the arm 25 from dropping to a position to open the motor circuit and lock the fan, and by reason of the rotation of wheel 30 as the arm 40 breaks its contact with one or the other of the terminals 43 or 52, the circuit of magnet 28 is broken and the full battery power is used on the motor circuit.

Having thus described my invention, what I claim as new and desire to secure by Letters Patent is—

1. In an elevator control, in combination with means for shutting off the power, a motor, means actuated by the motor for operating the first named means to elevator operating position, motor reversing means, means to hold the motor locked against movement, energizable means to actuate the locking means, a door actuated circuit closer, and electrical circuits including the motor;

the motor reversing means; the circuit closer and the energizable means whereby when the door is closed the motor will be momentarily operated to move the first named means to elevator operating position, and when the door is opened the motor will be reversely rotated to move said first named means to elevator non-operating position.

2. In combination with means for controlling the power of an elevator, a motor for operating said controlling means, a door controlled circuit closer, means to reverse the motor and an electrical circuit including the motor, circuit closer and reversing means, whereby when the door is closed the motor will be actuated to release the elevator power and when the door is open the motor will be reversed to shut off the elevator power.

20 3. In combination with an elevator power control and an electric rotary motor, means actuated by the motor to operate the power control, and electric means controlled by the elevator door which upon closing of the door rotates the motor to release the power and upon opening of the door reverses the motor to shut off the power.

4. In combination with an elevator power controlling means, a motor for operating said controlling means, a door controlled circuit closer, a reversing switch for the motor, means to lock the motor against movement, energizable means to operate the locking means, and electrical circuits including the motor, the circuit closer, the switch and energizable means whereby upon closing the door the circuit through the motor will be closed, and the motor operated to enable operation of the elevator and upon opening 40 of the door the circuit through the motor will reversely operate the latter, to prevent operation of the elevator.

5. In combination with an elevator power controlling means including a valve, a rotary motor, means operated by the motor rotations to actuate the valve, and electrical door controlled means for actuating the motor whereby when the door is closed the motor is rotated to open the valve and when the door is open the motor is reversely rotated to close the valve.

6. In an elevator control, in combination with means to shut-off and allow operation of the elevator, an electric rotary motor, means connected to said first means and operated by the motor rotations to control operation of said first means, and electric means controlled by the door whereby when the door is opened the motor will be rotated to shut off the first means and when the door is closed to reversely rotate the motor to move the first means to position to enable operation of the elevator.

7. In combination with an elevator control including a valve to control the power,

a motor having an arm connected thereto, means connected to the arm and valve for actuating the latter from the former, a door switch, and a reversing switch for the motor, and electrical connections between the motor, and the switches whereby when the door is closed the motor will be started to operate the arm to move the valve to open position and when the door is open the motor will be reversely operated to move 75 the arm in the opposite direction and move the valve to closed position.

8. In an elevator control, in combination with the power means for the elevator, an electric rotary motor, means controlled by the motor to open and to shut off the power, electric means to reverse the motor, and electric means controlled by the elevator door to rotate the motor whereby when the door is open the power will be shut off and when the door is closed the power will be restored.

9. In a hydraulic elevator control, means to shut off the power, an electric rotary motor, means operated by the motor rotations to actuate the shut off means, a reversing 90 electrical switch for the motor, a door switch, and electrical connections between said motor and switches whereby when the door is open the power is shut off and when the door is closed the power is restored.

10. In an elevator control, means for shutting off the power, a motor, means between the motor and shutting off means for operating the latter from the former, a reversing switch for the motor, means to lock the motor including a lever having a detent, a motor driven wheel having parts to interengage with the wheel, energizable means for operating the lever, means for electrically connecting the parts, means controlled by the door of the elevator whereby when the door is closed the energizable means will be energized to attract the lever, release the motor lock and establish a circuit through the motor and means whereby after the motor has operated a predetermined time the circuit through the motor will be opened by the wheel, the door when opened closing a circuit through the reversing switch to reverse the direction of rotation of the motor.

11. In an elevator control, in combination with means to control the power, a rotary motor, means operated by the rotary motor for actuating said power control means, and door controlled means to effect movement of 120 and to control the direction of rotation of the rotary motor.

12. In an elevator control, in combination with means to control the power, a rotatable electric driven element, means connected to said element and to the power control means to actuate the latter from the former, and electric door-controlled means to effect actuation of the element to render the power operative when the door is closed and to ren-

der the power inoperative when the door is open.

13. In an elevator control, in combination with means to control the power, an electrically driven motor, means operated by the motor to actuate said power control, an electrically operated reversing switch to control the electricity for driving the motor so as to reverse the latter, door controlled means to effect control of the normal and reverse mo-

tor movements, and electrical circuiting means including the motor, switch and door controlled means.

In testimony whereof I have signed my name to this specification in the presence of two subscribing witnesses.

ARTHUR WARD.
